CONTROL APPARATUS

Siegfried G. Isserstedt, Minneapolis, Minn., assignor to Minneapolis-Honeywell Regulator Company, Minneapolis, Minn., a corporation of Delaware

Application December 18, 1941, Serial No. 423,498

17 Claims. (Cl. 158—28)

This invention relates broadly to an automatic control system for a fluid fuel burner, and is more particularly directed to that type of apparatus employing a timing means for timing the various functions when the apparatus starts on an original call for heat and is shut down as a result of the demand for heat having been satisfied, or as a result of a flame failure at the burner.

The main purpose of this invention was to design an automatic control apparatus in which a very sensitive and fast acting combustion responsive device may be used. Where such a combustion device is used it is necessary to provide some means for delaying the restart of the burner motor following a shut-down, in order to provide for a proper scavenger period.

Another object of the invention is to provide a thermal timing means for timing the various functions referred to above.

A still further object of the invention is to provide a timing means which has a starting position and a running position, and in which the timer must be energized in one direction to cause it to move from its starting to its running position and then must be energized in the opposite direction to cause it to move from its running position to its starting position. The invention contemplates the use of a thermal timing means comprising a pair of thermal elements in which one of these elements is energized to move the timer from its starting to its running position and in which the other of the elements is energized to move the timer from its running to its starting position.

It is an object of this invention, not only to time the scavenger period for the burner by means of this thermal timer but also to delay the deenergization of the ignition device until a predetermined period of time after the establishment of combustion. In addition, the present invention contemplates utilizing this same thermal timer to operate a safety switch for the purpose of locking the apparatus out in the event that combustion is not established.

These and other objects will readily become apparent as the following specification is read in the light of the accompanying drawing which diagrammatically illustrates a control system embodying the various features of my invention.

My automatic control apparatus may obviously be placed under the control of many various types of condition responsive devices. For the purposes of illustration a room thermostat has been indicated generally at 10. This room thermostat is shown as comprising a bimetallic ele-

ment 11 which is fixed at one end and which carries at its free end a resilient contact blade 12 and a second contact blade 13 which cooperate respectively with the stationary contacts 14 and 15. The contacts 14 and 15 are so related to the two contact blades 12 and 13, that on a decrease in temperature the bimetallic element 11 will contract and first cause the resilient contact blade 12 to engage its stationary contact 14, and then on a further decrease in temperature will cause the contact blade 13 to engage its stationary contact 15.

A combustion responsive device is shown diagrammatically at 17. This device is shown as comprising an arm 18 which is adapted to be moved to the position shown in the absence of combustion at the burner and upon the establishment of combustion to move in a counter-clockwise direction. It is intended that this arm shall be moved upon the establishment or termination of combustion and therefore is not in any sense of the word a calibrated device. The free end of the arm 18 is connected to a switch arm 19 by means of the overcenter spring 20, so that upon the establishment of combustion the arm 18 will move the spring 20 overcenter with respect to the contact arm 19 which will be snapped from engagement with the cold contact 21 into engagement with the hot contact 22. Likewise, when combustion is terminated the arm 18 will again move the spring 20 overcenter with respect to the contact arm 19 which will then be snapped from engagement with its hot contact 22 into engagement with its cold contact 21.

Indicated at 25 is a double helix type bimetallic thermostat. For details of this thermostat see the F. A. Parsons Patent 2,121,259. This thermostat is composed of a relatively long strip of bimetal which is wound into the form of a helix and then that helix is again wound in the form of a larger helix to form in effect a double helix. The total length of the bimetal is extremely large with respect to its cross-sectional area and therefore this type of thermostat lends itself admirably to a system in which it is desired to heat a thermal element by passing current directly through the element itself.

The lower end of this thermal element is mounted at 26 upon one end of an arm 27 which 50 is pivotally mounted at 28. A second double helix type bimetal thermostat, which may be an exact duplicate of the thermostat 25 is mounted at 30 upon the opposite end of the pivoted arm 27. The opposite ends of the thermostats 25 and 29 are connected to the opposite ends of a hori-

zontal arm 31 which in turn carries an insulating member 32 which is guided as shown at 33 and 34. A coiled spring 35 loosely surrounds the insulating member 32 between the fixed guide member 33 and the arm 31 for a purpose which will be apparent later as this description proceeds. Indicated at 37 is a safety switch which comprises a pair of resilient contact blades 38 and 39 which are biased to open circuit position but which are held in circuit closed position by means of the insulating member 32 as shown in the drawing. If the insulating member 32 is raised, the out-turned end of the resilient blade 39 will drop off of shoulder 40 on the insulating member 32 and this blade will be released for movement to open circuit position. The shoulder 40 will then be latched on the end of the blade 39 and the switch 38, 39 will be effectively locked in open position until it is manually reset by means of the reset button 41. It will be noted that the long leg 42 of the reset button 41 will hold the switch blade 38 in open circuit position while the shorter leg on the switch button 41 is moving the blade 39 to the left in order to release the insulating member 32. This provides for a trip free reset, or in other words, prevents the switch 38, 39, from being manually held in closed position. It will be impossible to close the switch 38, 39 as long as the insulating member is in its raised position.

The insulating switch arm 45 is pivoted as shown at 46 and carries switch contact plates 47, 48 and 49 which cooperate with various stationary contacts as shown in the drawing. Switch arm 45 is connected to an extension 50 on the pivoted arm 27 by means of the over-center spring 51, so that as long as the pivoted arm 27 is in its mid-position as shown in the drawing the switch arm 45 will remain in either of its actuated positions. If the arm 27 is rotated in a clockwise direction, the spring 51 is carried overcenter with respect to the switch arm 45 and therefore this arm is snapped to its opposite position as shown in dotted lines on the drawing. In order to snap this arm back to the position shown on the drawing, the pivoted arm 27 must move in a counter-clockwise direction to the opposite side of its mid-position, thus carrying the overcenter spring 51 overcenter with respect to the switch arm 45.

My automatic control system also includes an electromagnetic relay which is diagrammatically shown as comprising a relay coil or winding 53 and an armature indicated by the dotted line 54. The armature 54 is adapted to actuate the relay switch arms 55, 56, 57, 58 and 59. When the relay coil 53 is deenergized the armature 54 is in its out position as shown in the drawing, but when the relay coil 53 is energized the armature 54 is in its in position and the various relay switch arms are in engagement respectively with their stationary contacts 60, 61, 62, 63 and 64.

My control system may be adapted to control many various types of devices for delivering fuel to a burner, but for the purposes of illustration the usual oil burner motor 66 has been illustrated. Also the usual electrical ignition device 67 for igniting the oil is shown.

Electrical power for my control system is supplied from a pair of line wires 68 and 10 which, through the conductors 71 and 72, supply power to the primary winding 73 of a step-down transformer 74. The transformer 74 is provided with a pair of secondary windings indicated at 75 and 76.

Operation

In the drawing, the room thermostat is shown in its satisfied position in which the contact blades 12 and 13 are out of engagement with their stationary contact 14 and 15. Therefore, there is no current flowing through the winding 53 of the relay and the armature 54 is in its out position. The burner motor and ignition device are therefore deenergized and there is no combustion present at the burner with the result that the switch arm 19 has been actuated by the combustion responsive arm 18 into engagement with its cold contact 21. There is no current flowing through the two thermostats 25 and 29 and therefore they are both at the same temperature, which is room temperature. The switch arm 45 is shown in its right-hand position. The safety switch 37 is also being held in closed position by means of the insulating member 32.

As a result of the above condition, the temperature in the room in which the thermostat 10 is located will begin to decrease and the bimetallic element 11 will first cause the resilient switch blade 12 to engage its stationary contact 14. This will not result in the establishment of a circuit at this time due to the fact that the relay switch arm 55 is out of engagement with its stationary contact 60. The emperature in the room will therefore continue to decrease until the bimetallic element 11 has contracted sufficiently to cause the switch blade 13 to engage its stationary contact 15. This results in the establishment of a circuit from one side of the secondary winding 75 through conductor 78, safety switch blades 38 and 39, conductor 79, contact 14, switch blades 12 and 13, contact 15, conductor 80, relay winding 53, conductors 81 and 82, switch plate 47, and conductors 83, 84 and 85 back to the other side of the secondary winding 75. This circuit energizes the relay winding 53 which immediately attracts the armature 54 and causes the relay arms 55 to 59 to move to their closed circuit position.

Engagement of relay arm 55 with its stationary contact 60 sets up a holding circuit from one side of the secondary winding 75 through conductor 78, safety switch blades 38 and 39, conductor 79, contact 14, switch blade 12, bimetallic element 11, conductor 86, contact 60, relay arm 5, conductor 87, relay winding 53, conductors 81 and 82, switch plate 47 and conductors 83, 84 and 85 back to the other side of the secondary winding 75. This circuit holds the relay winding 53 in, independently of the engagement of the switch blade 13 and contact 15, which very seldom make with a very good contact pressure.

Engagement of relay arm 59 with its stationary contact 64 establishes a circuit from the supply line 10 through conductor 89, contact 64, relay arm 59, conductors 90 and 91, burner motor 66, and conductor 92 back to the other supply line 69. A circuit through the ignition device 67 extends from the junction of conductors 90 and 91 through conductor 93, switch plate 48, conductor 94, ignition device 67, and conductor 95 back to the supply line 69. The above two circuits result in a delivery of fuel to the burner and the operation of the ignition device 67.

Engagement of the relay arm 57 with its stationary contact 62, establishes a circuit from one side of the secondary winding 76 through conductor 96, horizontal arm 31, thermostat 25, conductors 97 and 98, relay arm 57, contact 62, conductors 99 and 100, cold contact 21, switch arm

19, and conductors 101 and 84 back to the other side of the secondary winding 76.

Engagement of relay arm 58 with its stationary contact 63, establishes a circuit from one side of the secondary winding 76 through conductor 96, horizontal arm 31, thermostat 29, conductor 102, contact 63, relay arm 58, conductor 103, switch plate 47, and conductors 83 and 84 back to the other side of the secondary winding 76.

The last two circuits traced pass through the thermostats 25 and 29 and due to the resistance of the bimetal, generate heat therein, causing these two thermostats to expand. Inasmuch as there is equal heating of these two thermal elements, they tend to expand in the same direction and therefore there is no force tending to rotate the switch arm 27, this arm therefore remaining in its mid-position. The expansion of the elements 25 and 29, however, causes an upward movement of the horizontal arm 31 against the action of the spring 35, and after a predetermined period of time, if both of these circuits to the thermostats 25 and 29 remain closed, the insulating element 32 will be raised far enough to permit the out-turned end of the switch blade 29 to drop off the shoulder 40 and move to open circuit position. The opening of the safety switch 38, 39 results in the deenergization of the relay winding 53 and hence the deenergization of the burner motor 66 and ignition device 67. The system is therefore effectively locked out and will remain so until it is manually reset by means of the reset button 41.

The above sequence of operation takes place in the event combustion is not established as a result of the energization of the burner motor 66 and ignition device 67. Normally, combustion will be established before sufficient time has elapsed to open the safety switch 37. As soon as combustion is established, the combustion responsive arm 18 will snap the switch arm 19 from engagement with its cold contact 21 into engagement with its hot contact 22. The separation of the switch arm 19 from its cold contact 21 breaks the circuit through the thermostat 25, and therefore this thermostat stops heating and begins to cool, but the circuit through the thermostat 29 remains closed and therefore this thermostat continues to expand.

Engagement of the switch arm 19 with its hot contact 22 establishes a holding circuit for the relay coil 53 which extends from one side of the secondary winding 75 through conductor 78, safety switch blade 38 and 39, conductor 79, contact 14, switch blade 12, bimetallic element 11, conductor 86, contact 60, relay arm 55, conductor 87, relay winding 53, conductor 81, conductor 105, contact 61, relay arm 56, conductor 106, hot contact 22, switch arm 19, and conductors 101, 84 and 85 back to the other side of the secondary winding 75. It will be noted that this holding circuit is independent of the engagement of the contact plate 45 with its stationary contacts.

It was noted above that upon the establishment of combustion the thermostat 29 was expanding with respect to the thermostat 25. This results in a rotation of pivoted arm 27 in a clockwise direction which will carry the spring 51 overcenter with relation to the contact arm 45, which will result in this contact arm being snapped from the position shown in solid lines to the position shown in dotted lines in the drawing. This action breaks the original starting circuit to the relay winding 53 at 47, but this relay is held in by means of the holding circuit traced

above. It also breaks the circuit to the thermostat 29 and this thermostat therefore returns to the same temperature as the thermostat 25. In addition, it causes the contact plate 49 to engage its stationary contacts but this does not establish a circuit at the present time. It also causes the contact plate 48 to separate from its stationary contacts which results in the deenergization of the ignition device 67. This is the running condition of the circuit.

It will be noted at this time that the relay winding 53 was energized by a circuit passing through the hot contact 22 of the combustion responsive switch. Therefore, upon a failure of combustion at the burner the switch arm 19 will be caused to disengage the hot contact 22, which will result in deenergization of the relay winding 53. This drops out the armature 54 and deenergizes the burner motor 66. It will be noted that the relay winding 53 cannot again be energized until the switch arm 45 returns to its solid line position causing the contact plate 47 to engage its stationary contact.

When the combustion responsive arm 18 moves the switch arm 19 into engagement with the cold contact 21, it establishes a circuit from one side of the secondary winding 76 through conductor 96, horizontal arm 31, thermostat 25, conductors 97 and 108, contact plate 49, conductors 109 and 100, cold contact 21, contact arm 19 and conductors 101 and 84 back to the other side of the secondary winding 76. This circuit causes heating of the thermostat 25 which will expand and cause the arm 27 to rotate in a counter-clockwise direction which will result in the movement of the spring 51 overcenter with respect to the contact arm 45 which will then snap to its solid line position. The system will then recycle. The time required for the system to recycle is therefore determined by the time necessary for the thermostat 25 to heat sufficiently to return the contact arm 45 to its solid line position.

If the system is in running condition and the room thermostat becomes satisfied, the bimetallic element 11 will expand and cause the resilient contact blade 12 to separate from the stationary contact 14. This will deenergize the relay winding 53 which will in turn drop out the armature 54 and deenergize the burner motor 66. This in turn will terminate combustion at the burner and the combustion responsive arm 18 will snap the contact arm 19 out of engagement with the hot contact 22 and into engagement with the cold contact 21. This will establish the circuit through the thermostat 25, as traced above, which will return the contact arm 45 to its solid line position.

As many changes and modifications will doubtless occur to those who are skilled in the art, I wish it to be understood that I intend to be limited by the scope of the appended claims and not by the specific embodiment of my invention which has been disclosed herein for the purposes of illustration only.

I claim as my invention:

1. A fluid fuel burner control system comprising in combination, means for delivering fuel to a burner, timing means, a starting switch, a starting circuit including said starting switch for rendering said fuel delivery means operative, circuit control means closing said circuit in response to a demand for burner operation, means including said timing means, operative as a result of the closure of said starting circuit for setting up a holding circuit for said fuel delivery means and opening said starting switch, said circuit control

means opening said holding circuit and rendering said fuel delivery means inoperative when the demand for burner operation is satisfied, and means operative as a result of the deenergization of said holding circuit for energizing said timing means in a manner to cause it to reclose said starting switch.

2. A fluid fuel burner control system comprising in combination, means for delivering fuel to a burner, means for igniting the fuel, timing means, a starting switch, a starting circuit including said starting switch for rendering said fuel delivery means and ignition means operative, circuit control means closing said circuit in response to a demand for burner operation, means, including said timing means, operative as a result of the closure of said starting circuit for setting up a holding circuit for said fuel delivery means and opening said starting switch and also rendering said ignition means inoperative, said circuit control means opening said holding circuit and rendering said fuel delivery means inoperative when the demand for burner operation is satisfied, and means operative as a result of the deenergization of said holding circuit for energizing said timing means in a manner to cause it to reclose said starting switch.

3. A fluid fuel burner control system comprising in combination, means for delivering fuel to a burner, timing means, a starting switch, a starting circuit including said starting switch for rendering said fuel delivery means operative, circuit control means closing said circuit in response to a demand for burner operation, means operating in response to the establishment of combustion to set up a holding circuit for said fuel delivery means and energize said timing means in a manner to open said starting switch, either said circuit control means or said combustion responsive means being operative to open said holding circuit, and means operative as a result of the opening of said holding circuit for energizing said timing means in a manner to reclose said starting switch.

4. A fluid fuel burner control system comprising in combination, means for delivering fuel to a burner, means for igniting the fuel, timing means, a starting switch, a starting circuit including said switch for rendering said fuel delivery means and ignition means operative, circuit control means closing said circuit in response to a demand for burner operation, means operating in response to the establishment of combustion to set up a holding circuit for said fuel delivery means and energize said timing means in a manner to open said starting switch, render said ignition means inoperative, either said circuit control means or said combustion responsive means being operative to open said holding circuit, and means operative as a result of the opening of said holding circuit for energizing said timing means in a manner to reclose said starting switch.

5. A fluid fuel burner control system comprising in combination, means for delivering fuel to a burner, a timer member, a timing means which may be energized in a first direction to move said member from a first to a second position and may be energized in a second direction to move said member from said second to said first position, said timing means being inoperative to move said member when it is energized in both or neither directions, a starting switch closed by said timer member when it is in its first position, a starting circuit including said starting switch for rendering said fuel delivery means operative, means op-

erative as a result of the establishment of combustion to close a holding circuit for said fuel delivery means and energize said timing means in said first direction whereby said timer member is moved to said second position resulting in the opening of said starting switch, a second switch closed by said timer member in said second position, and circuit means operative upon the opening of said holding circuit to energize said timing means in said second direction to cause said timer member to reclose said starting switch, said circuit means including said second switch.

6. A fluid fuel burner control system comprising in combination, means for delivering fuel to a burner, a timer member, a timing means which may be energized in a first direction to move said member from a first to a second position and may be energized in a second direction to move said member from said second to said first position, said timing means being inoperative to move said member when it is energized in both or neither directions, a starting switch closed by said timer member when it is in its first position, a starting circuit including said starting switch for rendering said fuel delivery means operative, means operative as a result of the establishment of combustion to close a holding circuit for said fuel delivery means and energize said timing means in said first direction whereby said timer member is moved to said second position resulting in the opening of said starting switch, a second switch closed by said timer member in said second position, circuit means operative upon the opening of said holding circuit to energize said timing means in said second direction to cause said timer member to reclose said starting switch, said circuit means including said second switch, and switch means operated by said timer member to deenergize said timing means as said timer member moves from its first to its second position and from its second to its first position.

7. A fluid fuel burner control system comprising in combination, means for delivering fuel to a burner, means for igniting said fuel, a timer member, a timing means which may be energized in a first direction to move said member from a first to a second position and may be energized in a second direction to move said member from said second to said first position, said timing means being inoperative to move said member when it is energized in both or neither directions, a starting switch closed by said timer member when it is in its first position, a starting circuit including said starting circuit including said starting switch for rendering said fuel delivery means and said ignition means operative, means operative as a result of the establishment of combustion to close a holding circuit for said fuel delivery means and energize said timing means in said first direction whereby said timer member is moved to said second position resulting in the opening of said starting switch and the rendering of said ignition means inoperative, a second switch closed by said timer member in said second position, and circuit means operative upon the opening of said holding circuit to energize said timing means in said second direction to cause said timer member to reclose said starting switch, said circuit means including said second switch.

8. A fluid fuel burner control system comprising in combination, means for delivering fuel to a burner, a timer member, a timing means which may be energized in a first direction to move said member from a first to a second position and may

be energized in a second direction to move said member from said second to said first position, said timing means being inoperative to move said member when it is energized in both or neither directions, a safety member moved by said timing means when it is energized in both directions, a starting switch closed by said timer member when it is in its first position, a relay which, when energized, renders said fuel delivery means operative, a starting circuit for said relay including said starting switch, circuit control means closing said starting circuit in response to a demand for burner operation, means operating in response to the energization of said relay to energize said timing means in both directions, and means operated by said safety member for rendering said fuel delivery means inoperative after a predetermined period of time, means responsive to combustion, providing combustion is established before said fuel delivery means has been rendered inoperative, for causing energization of said timing means in the first direction only and for setting up a holding circuit for said relay, and means operating as a result of the deenergization of said relay for energizing said timer in the second direction.

9. A fluid fuel burner control system comprising in combination, means for delivering fuel to a burner, means for igniting said fuel, a timer member, a timing means which may be energized in a first direction to move said member from a first to a second position and may be energized in a second direction to move said member from said second to said first position, said timing means being inoperative to move said member when it is energized in both or neither directions, a safety member moved by said timing means when it is energized in both directions, a starting switch closed by said timer member when it is in its first position, a relay which, when energized, renders said fuel delivery means and said ignition means operative, a starting circuit for said relay including said starting switch, circuit control means closing said starting circuit in response to a demand for burner operation, means operating in response to the energization of said relay to energize said timing means in both directions, and means operated by said safety member for rendering said fuel delivery means and ignition means inoperative after a predetermined period of time, means responsive to combustion, providing combustion is established before said fuel delivery means has been rendered inoperative, for causing energization of said timing means in the first direction only and for setting up a holding circuit for said relay, said timer member opening said starting switch and rendering said ignition means inoperative, and means operating as a result of the deenergization of said relay for energizing said timer in the second direction.

10. A fluid fuel burner control system comprising in combination, means for delivering fuel to a burner, a timer comprising a timer member, a first thermal element which, upon being heated, drives said timer member from a first to a second position, a second thermal element which, upon being heated, drives said timer member from said second to said first position, said thermal element being incapable of moving said timer member when neither or both of them are heated, a starting switch closed by said timer member when it is in its first position, a relay which, when energized, renders said fuel delivery means

operative to deliver fuel to the burner, a starting circuit for said relay including said starting switch, means for closing said starting circuit in response to a demand for burner operation, means including a combustion responsive switch for setting up a holding circuit for said relay and causing heating of said first thermal element and not said second thermal element upon the establishment of combustion whereby said timer member is moved to its second position and opens said starting switch, and circuit means rendered operative as a result of the opening of said holding circuit for heating said second thermal element and not said first thermal element to cause said timer member to return to its first position.

11. A fluid fuel burner control system comprising in combination, means for delivering fuel to a burner, means for igniting said fuel, a timer comprising a timer member, a first thermal element which, upon being heated, drives said timer member from a first to a second position, a second thermal element which, upon being heated, drives said timer member from said second to said first position, said thermal elements being incapable of moving said timer member when neither or both of them are heated, a starting switch closed by said timer member when it is in its first position, a relay which, when energized, renders said fuel delivery means and igniting means operative to deliver fuel to the burner and ignite the same, a starting circuit for said relay including said starting switch, means for closing said starting circuit in response to a demand for burner operation, means including a combustion responsive switch for setting up a holding circuit for said relay and causing heating of said first thermal element and not said second thermal element upon the establishment of combustion whereby said timer member is moved to its second position and opens said starting switch and renders said igniting means inoperative, and circuit means rendered operative as a result of the opening of said holding circuit for heating said second thermal element and not said first thermal element to cause said timer member to return to its first position.

12. A fluid fuel burner control system comprising in combination, means for delivering fuel to a burner, a timer comprising a timer member, a first thermal element which, upon being heated, drives said timer member from a first to a second position, a second thermal element which, upon being heated, drives said timer member from said second to said first position, said thermal elements being incapable of moving said timer member when neither or both of them are heated, a starting switch closed by said timer member when it is in its first position, a relay which, when energized, renders said fuel delivery means operative to deliver fuel to the burner, a starting circuit for said relay including said starting switch, means for closing said starting circuit in response to a demand for burner operation, circuit means established as a result of the energization of said relay for simultaneously heating both of said thermal elements, a safety switch, means operated by said thermal elements for opening said safety switch, said last named means being operative only when both of said thermal elements are heated, means responsive to the establishment of combustion, provided combustion is established before said safety switch is opened, for setting up a holding circuit for said relay and opening the heat-

ing circuit for said second thermal element whereby only said first thermal element remains heated and said timer member moves to its second position, opening said starting switch and the heating circuit for said first thermal element, and means responsive to the termination of combustion at the burner for deenergizing said relay, providing said relay has not already been deenergized, and for heating said second thermal element whereby said timer member returns to its first position in which it opens the heating circuit for said second thermal element and recloses said starting switch.

13. A fluid fuel burner control system comprising in combination, means for delivering fuel to a burner, means for igniting said fuel, a timer comprising a timer member, a first thermal element which, upon being heated, drives said timer member from a first to a second position, a second thermal element which, upon being heated, drives said timer member from said second to said first position, said thermal elements being incapable of moving said timer member when neither or both of them are heated, a starting switch closed by said timer member when it is in its first position, a relay which, when energized, renders said fuel delivery means and igniting means operative to deliver fuel to the burner and ignite the same, a starting circuit for said relay including said starting switch, means for closing said starting circuit in response to a demand for burner operation, circuit means established as a result of the energization of said relay for simultaneously heating both of said thermal elements, a safety switch, means operated by said thermal elements for opening said safety switch, said last named means being operative only when both of said thermal elements are heated, means responsive to the establishment of combustion, provided combustion is established before said safety switch is opened, for setting up a holding circuit for said relay and opening the heating circuit for said second thermal element whereby only said first thermal element remains heated and said timer member moves to its second position, rendering said igniting means inoperative, opening said starting switch and the heating circuit for said first thermal element, and means responsive to the termination of combustion at the burner for deenergizing said relay, providing said relay has not already been deenergized, and for heating said second thermal element whereby said timer member returns to its first position in which it opens the heating circuit for said second thermal element and recloses said starting switch.

14. A thermal relay unit comprising a pivoted arm, a pair of thermally expandable elements connected at one end to said arm on opposite sides of its pivot, a member connecting the free ends of said thermal elements, and means for selectively heating said thermal elements, differentially to cause rotation of said arm, or to the same extent to obtain movement of said member.

15. A combination thermal timer and safety switch actuator comprising in combination, a ro-

tatably mounted switch actuating arm, a first thermal element mounted at one end of said arm, a second thermal element mounted at the other end of said arm, a safety switch, an actuating member for said safety switch mechanically connected to the opposite ends of said thermal elements, said rotatably mounted switch actuating arm assuming a mid-position when said thermal elements are at the same temperature, a snap action switch mechanically actuated by said rotatably mounted switch actuating arm, said rotatably mounted switch actuating arm being movable to one side of said mid-position to operate said snap switch to one position when said first thermal element is at a higher temperature than said second thermal element, said rotatably mounted switch actuating arm being movable to the other side of its mid-position to operate said snap switch to its other position when said second thermal element is at a higher temperature than said first thermal element, and means resisting movement of said actuating member for said safety switch, said thermal elements overcoming said resisting means to actuate said safety switch when said thermal elements are heated equally.

16. A thermal relay unit, comprising, a pair of thermal elements, first control means connected at its opposite ends to said thermal elements for actuation thereby, said means assuming a mid-position when said thermal elements are the same temperature and movable to either side of mid-position upon differential heating of either of said thermal elements, and a switch operated by said first control means, second control means connected to the opposite ends of said thermal elements, said second control means being movable in a longitudinal direction upon equal and substantial heating of both of said thermal elements, and a second switch operable by said second control means.

17. A fluid fuel burner control apparatus for controlling the operation of a fuel delivery means comprising in combination, a device including timing means, a starting switch, and means adapted for connecting said timing means and said starting switch in circuit relationship with a device which is responsive to a demand for heat to establish a starting circuit including said starting switch for rendering said fuel delivery means operative, said combination being adapted to close said circuit in response to a demand by said heat responsive device, means, including said timing means, operative as a result of the closure of said starting circuit for setting up a holding circuit for the operation of said fuel delivery means and opening said starting switch, said combination being adapted to open said holding circuit to render said fuel delivery means inoperative when the demand by said heat responsive device is satisfied, and means operative as a result of the de-energization of said holding circuit for energizing said timing means in a manner to cause it to re-close said starting switch.
